ATTORNEY.

UNITED STATES PATENT OFFICE.

ROBERT P. GARSED, OF NORRISTOWN, PENNSYLVANIA.

CAR-SIGNAL.

SPECIFICATION forming part of Letters Patent No. 276,801, dated May 1, 1883.

Application filed March 30, 1882. (No model.)

To all whom it may concern:

Be it known that I, ROBERT P. GARSED, a citizen of the United States, residing at Norristown, in the county of Montgomery, State of Pennsylvania, have invented a new and useful Improvement in Signals for Locomotive-Engines, which improvement is fully set forth in the following specification and accompanying drawings, in which—

10 Figure 1 is a vertical section of the signal embodying my invention. Fig. 2 is a vertical section of a modification thereof.

Similar letters of reference indicate corresponding parts in the two figures.

15 My invention consists in providing a locomotive-engine with a signal which indicates when it is in motion and at rest. For this purpose I employ the throttle-valve, which is within the dome of the engine, and connect therewith a pipe and signaling mechanism, whereby when the valve is operated to run or stop the engine steam is simultaneously admitted to said pipe and the signaling mechanism thereby operated, thus indicating whether 20 the engine is running or at rest.

25 Referring to the drawings, A represents the steam-dome of a locomotive-engine; and B represents a throttle-valve, which is sustained within said dome, and consists of a casing, a, and valve b, the inner face of the casing constituting the seat of the valve or piston, one end of the casing—in the present case the upper end—communicating with the dome.

30 In the wall of the casing a are two ports, c c', the port c communicating with a pipe, C, and the port c' with a pipe, D, the latter leading to the cylinder of the engine and the former to a barrel, E, which is properly supported in an upright position on the steam-dome, the valve 35 b serving to cover and uncover said ports c c'.

In the barrel E is a piston, F, to which is connected a stem, G, whose upper end has attached to it the base of a rising and falling box, H, which contains a lamp, J.

40 K represents a signal-lantern, which is secured to standards or supports d, connected to the barrel E, and within the lantern is fitted the lamp-box H.

45 It will be seen that the stem G of the piston F passes freely through the top of the barrel E and bottom of the lantern K, and the pipe C

communicates with said barrel below the piston F. The sides of the lantern K are formed of different-colored glass for night-signaling—in the present case green, as at e, and red, as 55 at e'—and the box H is half the height of the lantern, the sides of the box being open and the top and bottom thereof being closed, excepting at the center of the top, where there is an opening for the chimney or heat of the lamp. 60

The operation is as follows: When the engine is to be started the valve B is opened, this being accomplished in the present case by drawing down the valve b by means of the valve-rod b'. This uncovers the ports c c', 65 whereby steam passes from the dome through the pipe D to the cylinder of the engine, and through the pipe C to the barrel E, thus raising the piston F and shifting the lamp to the top of the lantern K, where the light of said 70 lamp illuminates the green glass e of the lantern, thus indicating that the engine is running, the piston F remaining elevated by the pressure of steam in the pipe C. When the valve b is raised steam is cut off from both 75 pipes C D, whereby the engine is stopped, and as steam in the pipe C condenses, the piston F is no longer under pressure, whereby the piston, and consequently the lamp, lowers, the 80 light from the lamp illuminating the red glass of the lantern, thus indicating that the engine is standing or at rest.

It will be noticed that, owing to the nature of the lamp-box H, both colored glasses are not illuminated at the same time, as the bottom or 85 top of said box acts as a shade, according to the position of the box, and thus confusion in the signals is prevented.

In Fig. 2 the valve b has a port, f, which communicates with the port c of the casing a in said figure when the engine is at rest, so that steam enters the pipe C and raises the lamp. When the engine is to be started the valve b is lowered, thus uncovering the port c' and closing the port c. Steam passes to the 90 cylinder of the engine, as usual, and also is cut off from the pipe C, whereby the lamp is permitted to lower. In this case the red glass is above and the green is below; but in either case the arrangement of the colors or nature 95 of the colors may be varied, according to the code of signals determined upon.

Having thus described my invention, what I claim as new, and desire to secure by Letters Patent, is—

1. The steam dome of a locomotive-engine, having within it a throttle-valve provided with an additional pipe which leads to signal-operating mechanism, said parts being combined substantially as described, whereby when said valve is operated to run or stop the engine the signal is simultaneously set, thus indicating that the engine is running or stopped.

2. The steam-dome of a locomotive-engine, having within it a valve to which are attached two pipes, one leading to the cylinder of the engine and the other to a barrel, the piston whereof is connected with a signaling device,

whereby when the valve is operated to run or stop the engine steam is simultaneously admitted to the aforesaid barrel or cut off therefrom, and the lamp of the signaling device is moved or set to indicate that the train is running or at rest, substantially as described.

3. The throttle-valve, with the pipe D and an additional pipe, C, communicating therewith, in combination with the barrel E, piston F, stem G, lamp-support H, and signal-lantern K, substantially as and for the purpose set forth.

R. P. Garsed.
